(57) CLAIM

(21) Appl. No.: **29/156,919**

We are claiming the ornamental appearance of a dishwasher front door and panel, as shown and described.

(22) Filed: **Mar. 8, 2002**

DESCRIPTION

(51) LOC (7) Cl. **15-05**

FIG. 1 is a front perspective view of the design of the present invention.

(52) U.S. Cl. **D32/3**

FIG. 2 is a front elevational view thereof,

(58) Field of Search **D32/1-3, 5-6, D32/8, 25; 137/374; 15/DIG. 7; 134/135, 56 D, 58 D, 57 D; 312/109; 68/3 R, 12.27; D8/317, 349**

FIG. 3 is a top plan view thereof,

(56) References Cited

FIG. 4 is a right side elevational view thereof; and,

FIG. 5 is a left side elevational view thereof.
